(57) **CLAIM**

I claim the ornamental design for the cooler, as shown and described.

DESCRIPTION

FIG. 1 is a front view of the cooler showing my new design.

FIG. 2 is a rear view thereof.

FIG. 3 is a top plan view thereof.

FIG. 4 is a bottom plan view thereof.

FIG. 5 is a left side view thereof.

FIG. 6 is a right side view thereof; and,

FIG. 7 is a perspective view thereof.

The shade lines in the Figures show contour and are not

surface ornamentation.
